LEONARD ROSE, OF NEW ORLEANS, LOUISIANA.

SPARK-PLUG.

1,178,538.

Specification of Letters Patent. Patented Apr. 11, 1916.

Application filed January 21, 1915. Serial No. 3,572.

To all whom it may concern:

Be it known that I, LEONARD ROSE, a subject of the King of Great Britain, residing at New Orleans, in the parish of Orleans and State of Louisiana, have invented a new and useful Spark-Plug, of which the following is a specification.

This invention has reference to spark plugs, and is designed to provide a spark plug wherein access of oil and soot to the insulating member of the spark plug is prevented and the cleansing of the interior of the spark plug from accumulations of either oil or soot or both is facilitated.

In accordance with the present invention the spark plug comprises a body member which may be made, as is the custom, of a metal, such as brass, and within the body portion is a chamber or cavity opening through the sparking end of the plug by way of a suitable passage traversed by the insulated terminal or electrode, while the other end of the chamber is closed by the corresponding end of a porcelain or other insulating block through which the stem of the central terminal extends, and beyond which such stem is accessible.

The present invention has to do with the so-called anti-soot type of spark plugs, and in such spark plugs trouble has been experienced from short-circuiting due to accumulations of oil and soot or other foreign matter on the porcelain or other suitable insulator.

By the present invention any soot or oil which may find its way into the interior of the spark plug is directed into an inverted cup which in turn directs any such matter to the bottom of the internal chamber where it is entirely harmless, and from which the accumulated matter may be removed from time to time as needed without removing the spark plug from the engine.

The invention will be best understood from a consideration of the following detailed description taken in connection with the accompanying drawings forming a part of this specification with the further understanding that while the drawings show a practical form of the invention, the latter is not confined to any strict conformity with the showing of the drawings, but may be changed and modified so long as such changes and modifications mark no material departure from the salient features of the invention.

In the drawings:—Figure 1 is an elevation of a spark plug constructed in accordance with the present invention. Fig 2 is a longitudinal diametric section. Fig. 3 is a section on the line 3—3 of Fig. 2.

Referring to the drawings there is shown a body member 1 inclosing a chamber 2, and at one end provided with an axial externally threaded neck 3 having an axial bore 4 therethrough. The end of the body member 1 remote from the neck 3 is formed into a laterally expanded and axially extended cup 5 provided with internal screw threads and external plane faces arranged to form the customary hexagonal nut for the application of a tool. At the junction of the chamber 2 with the interior of the cup 5 there is formed a shoulder 6.

Adapted to the cup 5 is one end of an elongated block 7 usually of porcelain, but which may be made of any suitable insulating material. The block 7 will hereinafter be referred to as a porcelain block without, however, any limitation of this part of the structure to such specific material.

As a convenient means for holding the porcelain block 7 in the cup 5 the block is formed at that end entering the cup with an exterior radially extended flange 8 which may be clamped against the shoulder 6 through the intermediary of a gasket 9 usually, though not necessarily, a copper gasket. Applied to the other face of the flange 8 from the gasket 9 is a second sealing gasket 10 which may also be a copper or other like gasket. Screwed into the cup 5 is the customary annular nut 11 having a rim 12 at one end for the application of a tool, wherefore this rim is usually made of hexagonal contour. When the nut 12 is screwed into place the flange 8 is held between two sealing gaskets which may both be alike with the gasket 9 against the shoulder 6, so that leakage of gases of explosion is prevented.

Extending longitudinally through the block 7 is a passage 13 traversed by a metal stem 14 having at one end a head 15 which in the particular showing of the drawings is multi-pointed. The passage 13 may be and is of considerably less diameter than the passage 4 and the head 15 is of a diameter but little less than that of the passage 4 so that it may traverse the passage 4. The stem 14 substantially corresponds in diameter to the passage 13 so as to fit the porcelain block

2
easily and yet comparatively snugly. The rod or stem 14 is threaded for an appropriate distance, the threaded portion being longer than the length of the block 7 and the stem 5 is of sufficient length to extend beyond the outer or upper end of the block 7 when the head 15 is beyond or below the free or lower end of the neck 3. Applied to the stem 14 above the block 7 is a nut 15^a with washers 10 16 of some suitable soft material which is appropriately resistant to heat. Ordinarily asbestos washers 16 are employed. The nut 15^a may have its exterior milled for convenience of manipulation, or it may be otherwise formed for the application of a tool. Beyond the nut 15^a the rod 14 receives a clamp nut 17 which in the particular showing of the drawings is provided with a handle 18, but it will be understood that any form of 15 nut whereby an electric conductor may be clamped against the nut 15^a may be employed.

Within the chamber 2 which is traversed by the rod or stem 14 with its threaded portion entering the chamber, is a cup 19 having at its closed end a hub 20 appropriately axially threaded so that the cup may be screwed along the rod or stem 14 with the cup concentric with the rod, and its open 25 end directed toward the neck end of the body 1. Rising from the bottom of the chamber 2, considering the spark plug as upright, is a tube 21 with its interior constituting a continuation of the bore 4. This 30 tube 21 is of sufficient length to enter the lower open end of the cup 19 for a portion of the depth of the cup and the tube opens toward the closed end of the cup while the open end of the cup opens toward the bottom 35 of the chamber 2.

By a suitable adjustment of the nut 15 the central terminal represented by the head 15 is brought into proper relation to the lower end of the neck 3 which constitutes the other terminal of the spark plug. This adjustment may be properly made before the plug is introduced into the engine, and may be afterward changed as circumstances may demand by removing the body 50 of the plug from the engine.

With a spark plug such as described the head 15 when quite close to the neck 3 prevents to some extent access of oil or soot or both to the interior of the spark plug 55 through the passage 4, but it is not at all detrimental to the proper operation of the spark plug for oil or soot or both or other material to find its way into the interior of the spark plug through the passage 4 and tube 21, since such material does not then reach the porcelain block 7 where facing the chamber 2, because it is deflected therefrom by the inverted cup 19. The oil or soot may under the force of the explosion enter the 60 chamber 2 under considerable headway, but

on reaching the interior of the cup 19 the direction of movement of such oil or soot is changed, so that instead of following the initial direction of movement toward the block 7 such course is changed, whereby the 70 soot and oil are deflected toward the bottom of the chamber 2 where such materials may accumulate without harm, since they can neither reach the porcelain block 7 nor the central stem 14, wherefore there is no 75 possibility of a short circuit being established and the operation of the spark plug being prevented thereby.

The cup 19 serves both the purpose of a lock nut for the stem 14 and a deflector for 80 any oil, soot or other material projected into the interior of the spark plug toward the porcelain insulator, wherefore such material cannot reach the insulator and so act to the detriment of the electrical efficiency 85 of the spark plug.

The chamber 2 is readily cleansed of accumulations from time to time by removing the block 7 and parts carried thereby.

What is claimed is:—

1. A spark plug comprising a body portion with an interior chamber accessible to gases of explosion through the active end of the plug, a block of insulating material closing that end of the chamber remote from the active end of the spark plug, a rod extending through the block of insulating material and chamber and screw-threaded for the greater portion of its length, whereby the screw threads extend beyond both 95 ends of the insulating block, and said rod having a spark plug terminal in operative relation to the active end of the plug, a cup threaded on the rod within the chamber with the mouth of the cup in the path of incoming gases of explosion and material carried thereby for diverting such material away from the insulating block, and a tubular duct for the gases of explosion with 100 in the chamber and telescoping into the cup toward the closed end thereof.

2. A spark plug comprising a body member with a chamber therein opening through the active end of the plug and there accessible to gases of explosion, a block of insulating material carried by the body member and forming a closure for that end of the chamber remote from the active end of the plug, a threaded stem extending lengthwise through the block and through the active end of the plug and there provided with a spark terminal, the threaded portion of the stem being of a length to project beyond both ends of the block of insulating material, a cup within the chamber threaded on the rod and having its mouth in the path of gases of explosion entering the chamber, a duct within the chamber for directing the gases of explosion into the cup, and said duct being telescoped into the cup, and a 115 120 125 130 135

clamp nut applied to the end of the rod projecting beyond the insulating block at the end of the latter remote from the chamber and coacting with the threaded cup to 5 clamp the rod to the insulating block to provide for adjustment of the spark plug terminal carried by the rod with relation to the active end of the spark plug and with the cup always in the same relation to the tubular duct irrespective of such adjustments.

In testimony, that I claim the foregoing as my own, I have hereto affixed my signature in the presence of two witnesses.

LEONARD ROSE.
